JOHN MAGEE, OF NEW YORK, N. Y., ASSIGNOR TO BIGELOW CARPET COMPANY, OF CLINTON, MASSACHUSETTS.

Design No. 5,033, dated June 20, 1871.

DESIGN FOR CARPET.

The Schedule referred to in these Letters Patent and making part of the same.

To all whom it may concern:

Be it known that I, JOHN MAGEE, of the city of New York, in the county and State of New York, have invented a new and original Design for a Carpet; and do hereby declare that the following is a full, clear, and exact description thereof, which will enable others skilled in the art to make and use the same, reference being had to the accompanying drawing forming part of this specification.

The photograph represents my new design.

The nature of my design is fully represented in the accompanying photographic illustration, to which reference is made.

I claim as my invention—

The design for a carpet, as shown.

JOHN MAGEE.
